United States Patent Office

Des. 188,187
Patented June 14, 1960

188,187

BUILDING BLOCK

Bernard K. Rose, 69 N. Glenwood Road, Fanwood, N.J.

Filed Oct. 1, 1959, Ser. No. 57,752

Term of patent 14 years

(Cl. D18-2)

Fig. 1

I claim:

The ornamental design for a building block, as shown.
